METAL PIPE

James D. Sample, Birmingham, Ala., assignor to
McWane Cast Iron Pipe Co., Birmingham, Ala.

Application January 16, 1935, Serial No. 2,110

2 Claims. (Cl. 138—47)

This invention relates to new and useful improvements in metal pipes.

Heretofore, it has been the practice to form cast iron pipes with threaded ends which necessarily reduced the strength of said ends. Originally these pipes were of uniform diameters throughout their lengths, and as a result of contraction and different strains and stresses and combination of these factors, the pipes would often break at the inner end of the threads. This condition was corrected by increasing the stock at the threaded ends of the pipe to thereby provide either an increased exterior diameter or a decreased interior diameter to said ends. However, a pipe having an increased diameter at its ends was not suitable for use with fittings having nominal size threads; a pipe having a decreased interior diameter throughout the entire length necessarily reduced the carrying capacity of the pipe, and the additional metal employed in both forms necessarily increased the cost of manufacture a corresponding amount.

It is, therefore, the principal object of the present invention to provide a cast metal pipe having uniform exterior and interior diameters throughout its length and constructed in such a manner that the pipe will better resist breaking at either or both of its threaded ends.

Another object of the invention is to provide a cast metal pipe having a body of ordinary strength, and relatively higher strength end sections or sections, the latter receiving the threads which terminate at points in spaced relation to the unions between the body and the end sections whereby the points of strains will be located in spaced relation to the inner ends of the threads.

With these and other objects in view which will more fully appear, the nature of the invention will be more clearly understood by following the description, the appended claims, and the several views illustrated in the accompanying drawings.

In the drawings:—

Figure 1 is a longitudinal section showing a nonthreaded cast metal pipe constructed in accordance with my invention.

Figure 2 is a similar view but showing the pipe with threaded ends.

Figure 3 is a front elevation of the apparatus employed in carrying out my process of casting the pipe shown in Figure 1.

Figure 4 is a top plan view thereof, and Figure 5 is an end elevation of the same, the mold being shown in section.

Like reference numerals designate corresponding parts throughout the several figures of the drawings.

Referring to the accompanying drawings, my improved cast metal pipe A is shown in Figure 2, wherein the pipe is of uniform exterior and interior diameters throughout its entire length. The pipe includes a relatively long body section 5 and relatively short end sections 6, 6. The body section is formed of ordinary strength metal 10 such as cast iron and either or both end sections are formed of relatively higher strength alloy metal such as an alloy of cast iron, with molybdenum and/or chromium. However, it will be understood that these end sections may be formed from any one or any combination of the following metals with cast iron:

Molybdenum	20
Chromium	
Nickel	
Titanium	
Zirconium	

It will be understood, that either or both end sections may be formed of relatively higher strength metal than the body. After the pipe has been thus formed by casting, the end sections are then formed with exterior threads 1, 1, the inner ends 8, 8 of said threads terminating in spaced relation to the points of union 9, 9 between the end sections 6, 6 and the body section 5.

My improved pipe is cast by the following process:—A horizontal mold B is provided which consists of the usual cope 10 and drag 11. Supported within the mold are two pipe cores 12, 12 which are supported horizontally in the usual manner and leading to these cores and to the mold cavity is a plurality of spaced gates 13, there being one of these gates for each end section 6 of the pipe, and a plurality of these gates for the body section 5 of the pipe. These gates are preferably spaced apart at substantially equal distances. A ladle C is associated with the mold and this ladle is provided with a plurality of pour lips 14, there being as many lips as gates, and the lips being arranged in register therewith. The ladle C includes the usual side walls 15, 16 and end walls 17, 17. The ladle, however, is divided by means of partitions 18, 18 into three compartments consisting of end compartments 19, 19 and a central compartment 20. The number of end compartments, however, is dependent upon the casting of either one or both ends of higher strength alloy metal. The end pouring

lips 14, 14 are respectively associated with the end compartments 19, 19 and the intermediate pouring lips are associated with the central compartment 20.

5 While I have shown a single ladle formed of a plurality of compartments, it will be understood that a plurality of separate ladles may be employed if so desired.

Molten iron is poured into the central compartment 20 and the relatively higher strength metal is poured into the end compartments 19, 19. The ladle is then tilted and the ordinary strength metal or iron flows from the intermediate lips 14 simultaneously and at substantially the same rates into the intermediate gates 13, and the higher strength alloy metal flows from the end lips 14, 14 simultaneously and at substantially the same rate into the end gates 13, 13 causing the levels of the two metals to rise together. By reason of the gates 13, 13 being spaced approximately equidistantly apart, the molten metal will be distributed evenly and will of course flow in opposite directions, and consequently the points of union 9, 9 as shown in Figure 2, between the ordinary and higher strength alloy metals will be located at points substantially intermediate the outer pairs of lips 14. Although points of union 9 are shown in the drawings in order to indicate that the end portion 30 is constituted differently from the body portion, it will be understood that there is no clearly defined or sharp line of demarcation between the metals of the two portions, since the molten metal in the body portion will be in contact with the molten metal in the end portion when the pipe is being cast. Consequently, the end portion will merge with the body portion, the metal in the merging ends of said portions comprising an intermixture of body portion metal and end portion metal.

After the casting has been removed from the

mold and cooled, one or both end sections 6 are then provided with exterior threads 1, the inner ends of said threads terminating in spaced relation to the points of union 9 between the ordinary and higher strength alloy metals.

From the foregoing, it will be observed that I have provided a bi-metal cast pipe with threaded end sections formed of higher strength alloy metal than the body section; that the points of union between these metals are located in spaced relation to the inner ends of the threaded ends; that the pipe thus formed is of uniform exterior and interior diameters throughout its length; that by constructing a pipe in this manner sufficient strength is imparted to the end sections whereby liability of breaking due to contraction or various strains and stresses will be reduced to a minimum; and the strength of one or both end sections after threading is closely comparable to the strength of the body.

I claim:—

1. A pipe of cast metal comprising a body portion and a threaded end portion merging therewith, the end portion comprising alloy metal which is relatively stronger than the metal comprising the body portion, the metal in the merging ends of said portions comprising an intermixture of the metal of the body portion and the metal of the end portion.

2. A pipe of cast metal comprising a body portion and a threaded end portion merging therewith, the end portion comprising alloy metal which is relatively stronger than the metal comprising the body portion, the metal in the merging ends of said portions comprising an intermixture of the metal of the body portion and the metal of the end portion, said portions having a substantially uniform diameter throughout their lengths.
